TAPERING ATTACHMENT FOR BORING
MACHINESHarold H. Bauer, Montgomery County, near
Dayton, Ohio

Application September 4, 1936, Serial No. 99,434

8 Claims. (Cl. 77—58)

This invention relates to new and useful improvements in a Tapering attachment for boring machines.

It is one of the principal objects of my invention to provide a compact and efficient taper-boring chuck that may be easily attached to any boring mill, jig-borer, or the like.

My taper-boring chuck makes it possible to apply the taper-boring device to the rotating tool of a boring machine, whereas at present it is necessary to do all taper boring in a lathe where the work rotates, or by the use of taper reamers.

The hole bored by my taper-boring chuck will be smooth and straight, and at the exact angle 15 at which the taper-control bar is set.

It is a further object of my invention to provide special cam bars for substitution for the straight taper cam bar in my taper-boring chuck, to bore holes of special contours, such as the 20 holes of uneven longitudinal contours in moulds for glassware, bakelite and the like.

Other important and incidental objects will be brought out in the following specification, and particularly set forth in the subjoined claims.

In the accompanying drawings illustrating various forms of embodiment of my invention, Figure 1 is a horizontal, perspective view showing my taper-boring apparatus attached to a boring mill. Figure 2 is a vertical, perspective view of my taper-boring apparatus attached to a jig-borer. Figure 3 is a vertical, sectional view taken through my taper-boring chuck and attachment for controlling the taper. Figure 4 is a vertical, sectional view taken through the same at right angles to the plane of the section through Figure 3.

Figure 5 is a bottom plan view thereof. Figure 6 is a cut-away enlarged, vertical sectional view taken through the taper boring mechanism. Figure 7 is a vertical, sectional view taken through a modified form of my taper-boring mechanism, in which a straight cam bar is replaced with a special bar of predetermined contour. And Figure 8 is a vertical, sectional view taken through 45 a piece of metal containing a hole bored by my taper-boring chuck employing the special cam bar illustrated in Figure 7.

Referring to the accompanying drawings for a detailed description of the various forms of embodiment of my invention illustrated therein, the numeral 1 in Figure 1 designates a boring mill to the spindle 2 of which my taper-boring chuck 3 is attached. In Figure 2 the taper-boring chuck 3 is shown attached to the spindle 4 of a jig-borer 5. My taper-boring chuck 3 preferably comprises

an accurately ground shell or body 6 having an open internally threaded top into which a cap 7 is threaded and locked in place by two set screws 8 to insure solidity and concentric rotation of the body. This cap, due to its threaded fit, permits of proper adjustment to prevent any looseness of the primary tool head section 9. The top of the cap 7 contains an internally threaded recess 10 to receive the threaded lower end 11 of a shank 12 which is fitted into the spindle of the 10 machine. In Figure 1 it is shown fitted into the spindle 2 of a boring mill 1, whereas in Figure 2 it is attached to the spindle 4 of a jig-borer 5.

The primary tool head section 9, which is radially or transversely slidable in the shell or body 6, 15 carries an adjustable sine-bar or cam bar 13 that is pivotally secured to a boss 14 on the inner end thereof by a pin 15. The outer end of the primary tool head section 9 is formed with a lateral threaded hole containing the shank of an 20 adjusting screw 16 whose head 17 is fitted in a recess 18 in the free end of the cam bar. (See Figures 3 and 6).

The cam bar 13 is maintained in contact with the head of the adjusting screw 16 by a draw rod 25 19 connected at its outer end to a pin 20 within a recess 21 in its upper middle portion. The draw rod 19 passes through a lateral hole 22 in the primary tool head section 9, into a counterbore 23 in the latter, and through said counterbore 30 into an enlarged recess 24 in said offset. A compression spring 25 surrounds the draw rod 19 between the inner end of the counterbore 23 and a retaining washer 26 carried by the inner end of said rod. This spring exerts an inward pressure 35 upon the rod 19 to cause it to draw the cam bar 13 into engagement with the head of the adjusting screw 16.

For the purpose of boring straight holes I provide an auxiliary stop screw 27 in the primary 40 tool head section 9, for engagement by the cam bar 13 to hold it parallel with the axis of the chuck when the adjusting screw 16 has attained its maximum inward movement.

The primary tool head section 9 projects 45 through a slot 28 in the bottom of the body 6 for guidance during its transverse or lateral movement. (See Figures 3 and 5).

Fitted in the lower end of the primary tool head section 9 is a secondary tool head section 29 that 50 is made adjustable therein by a micrometric screw 30. The primary tool head section 9 and the secondary tool head section 29 are formed with complementary semi-cylindrical, threaded recesses which receive the screw 30. A tongue 31 is 55

provided on the primary tool head section for entrance into an annular groove in the screw, whereby, when the screw is turned, the secondary tool head section will be moved laterally independent of the primary tool head section.

The secondary tool head section 29 is provided in its bottom portion with a recess 32 to receive a boring tool or bar 33 which is securely fastened therein by a lock screw 34. (See Figures 1 and 6.) The secondary tool head section 29 may also be locked in position within the primary tool head section 9 by a lock screw 35 operable through a slot 36 in the chuck body 6.

Transverse movement of the primary tool head section 9 is effected by the pressure exerted upon it by a ring 37 carried by an annular thrust bearing 38 mounted in a flanged supporting ring 39. The latter is secured by screws 40 to the outer ends of supporting arms 41, 41 whose inner ends 20 are attached by screws 42 to the jig borer head 43 shown in Figure 2, and to the flange ring 44 on the spindle quill 45 of the boring mill 1 illustrated in Figure 1.

When during the boring operation the chuck body 6 moves downwardly through the ring 37, the latter will engage the cam bar 13 and move it inwardly. The inwardly moving cam bar will then, through the screw 16, press inwardly the primary tool head section 9 to which the secondary tool head section 29, carrying the boring tool 23, is attached. Therefore, when the boring tool is rotated by the spindle 2 in the boring mill 1 in Figure 1, or by the spindle 4 in the jig borer 5 in Figure 2, it will bore a hole of the desired 30 straight taper in the work being operated upon.

The desired taper of the hole to be bored is obtained by an adjustment of the screw 16 before the boring operation is started. The head of this screw is engaged by the free end of the cam bar 13, to move the primary tool head section 9 inwardly when the said cam bar is engaged by the draw ring 37 as the chuck body 6 is forced through it by the spindle.

The secondary tool head section 29 may be adjusted by the micrometric screw 30 to predetermine the diameter of the hole to be bored.

A compression spring 52 is inserted between the primary offset and the interior surface of the shell diametrically opposite the cam bar 13, to maintain constant contact between the latter and the ring 37. (See Figure 3.)

In Figure 7 I have illustrated a modified form of cam bar for my taper-boring chuck. In this instance the adjustable cam bar 13 is made in two parts, the inner part 46 being hingedly connected to the primary tool head section 9 for engagement at its upper end with the head of the adjusting screw 16. Secured to the inner part 46 of this cam bar by fastening means such as screws 47 and dowel pins 48 is an outer part 49. The latter part is formed in a shape designed to effect the boring of a hole of a special contour in a metal piece. Such a hole 50 is illustrated as having been bored in the piece 51, illustrated in Figure 8. While the contour of this hole is concentric with its axis, it is uneven longitudinally, as is often the case with holes in moulds for glassware, bakelite and the like. Such holes can be bored only when my taper boring chuck employing the two-part cam bar is used, since the ring 37 will follow the uneven contour of the outer part of the cam bar to impart the proper lateral movement to the primary tool head section 9 to position the boring tool at the angles 70 required to bore a hole of the desired uneven

longitudinal contour. At present such holes can only be bored by the use of a templet on a lathe, which requires considerable time and labor.

The outer part 49 of the two-piece cam bar may be easily replaced by a straight bar to effect straight taper boring operations.

Having described my invention, I claim:

1. A boring apparatus having a jig borer head, a frame projecting axially from said head, a spindle rotatably and longitudinally movable in said frame, a shell secured to said spindle, a tool head transversely movable in said shell, a boring tool carried by said tool head, a ring supported by the frame and held against movement axially of the spindle, a cam bar pivotally secured at one end to the shell for contact with said ring through which it is forced by the spindle, and an adjustable connection between the free end of the cam bar and the tool head whereby, when the free end of said bar is forced inwardly by the ring while the shell passes therethrough, the tool head carrying the boring tool will be moved inwardly by said adjustable connection to produce a tapered hole.

2. A boring apparatus having a jig borer head, a frame projecting axially from said head, a spindle rotatably and longitudinally movable in said frame, a shell secured to said spindle, a tool head transversely movable in said shell, a boring tool carried by said tool head, a ring supported by the frame and held against movement axially of the spindle, a cam bar pivotally secured at one end to the shell for contact with said ring through which it is forced by the spindle, and an adjustable connection between the free end of the cam bar and the tool head whereby, when the free end of said bar is forced inwardly by the ring while the shell passes therethrough, the tool head carrying the boring tool will be moved inwardly by said adjustable connection to produce a tapered hole.

3. A boring apparatus having a jig borer head, a frame projecting axially from said head, a spindle rotatably and longitudinally movable in said frame, a shell secured to said spindle, a tool head transversely movable in said shell, a boring tool carried by said tool head, a ring supported by the frame and held against movement axially of the spindle, a cam bar pivotally secured at one end to the shell for contact with said ring through which it is forced by the spindle, an adjustable member carried by the tool head and projecting beyond the latter for engagement by the free end of the cam bar, whereby, when the free end of said bar is forced inwardly by the ring while the shell passes therethrough, the tool head carrying the boring tool will be moved inwardly by said adjustable member to produce a tapered hole.

4. A boring apparatus having a jig borer head, a frame projecting axially from said head, a spindle rotatably and longitudinally movable in said frame, a shell secured to said spindle, a tool head transversely movable in said shell, a boring tool carried by said tool head, a ring supported by the frame and held against movement axially of the spindle, a cam bar pivotally secured at one end to the shell for contact with said ring through which it is forced by the spindle, an adjustable member carried by the tool head and projecting beyond the latter for engagement by the free end of the cam bar, a draw rod carried

by the tool head and secured at one end to the cam bar, and a compression spring on said rod for drawing it, and the free end of the cam bar inwardly, to maintain the latter in contact with 5 the adjustable member whereby, when the free end of said cam bar is forced inwardly by the ring while the shell passes therethrough, the tool head carrying the boring tool will be moved inwardly by the adjustable member to produce 10 a tapered hole.

5. A boring apparatus having a jig borer head, supporting arms attached and projecting axially from said head, a spindle rotatably and longitudinally movable within the space defined by 15 said arms, a shell secured to said spindle, a boring tool carried by said tool head, a supporting ring secured to the outer ends of said arms, a ring supported by said first ring through which the shell is forced by the spindle, the second ring 20 being held by the first ring against movement axially of the spindle, a cam bar pivotally secured at one end to the shell for contact with the second ring through which it is forced by the spindle, and a connection between the free end 25 of the cam bar and the tool head whereby, when the free end of the cam bar is forced inwardly by the second ring while the shell passes therethrough, the tool head carrying the boring tool will be moved inwardly by said connection to produce 30 a tapered hole.

6. A boring apparatus having a jig borer head, a frame projecting axially from said head, a spindle rotatably and longitudinally movable in said frame, a shell secured to said spindle, a tool 35 head transversely movable in said shell, a boring tool carried by said tool head, a ring supported by said frame and held against movement axially of the spindle, a cam bar pivotally secured at one end to the shell for contact with said ring 40 through which it is forced by the spindle, an adjustable screw carried by the tool head and projecting beyond the latter for engagement by the free end of the cam bar, and a stop also carried by the tool head to engage the cam bar and 45 hold it parallel with the axis of the shell when said adjusting screw has attained its maximum inward movement, the tool head carrying the boring tool adapted to be moved inwardly by the adjustable screw to produce a tapered hole when

the free end of said bar is forced inwardly by the ring while the shell passes therethrough.

7. A boring apparatus having a jig borer head, a frame projecting axially from said head, a spindle rotatably and longitudinally movable in 5 said frame, a shell secured to said spindle, a tool head transversely movable in said shell, a boring tool carried by said tool head, a ring supported by the frame and held against movement axially of the spindle, a cam bar pivotally secured at 10 one end to the shell for contact with said ring through which it is forced by the spindle, an adjustable member carried by the tool head and projecting beyond the latter for engagement by the free end of the cam bar, and resilient means 15 carried by the tool head and attached to the cam bar to draw it into engagement with the outer end of the adjustable member, and means having an outer curved surface attached to the cam bar whereby, when said surface is engaged by the 20 ring, the tool head will be moved by the adjustable member to produce a hole of special contour that is predetermined by the shape of said outer surface of the last said means.

8. A boring apparatus having a jig borer head, 25 a frame projecting axially from said head, a spindle rotatably and longitudinally movable in said frame, a shell secured to said spindle, a tool head transversely movable in said shell, a boring tool carried by said tool head, a ring supported 30 by the frame and held against movement axially of the spindle, a cam bar pivotally secured at one end to the shell for contact with said ring through which it is forced by the spindle, an adjustable member carried by the tool head and 35 projecting beyond the latter for engagement by the free end of the cam bar, resilient means carried by the tool head and attached to the cam bar to draw it into engagement with the outer end of the adjustable member, and a member 40 having an outer curved surface removably attached to the cam bar, whereby, when said surface is engaged by the ring, the tool head will be moved by the adjustable member to produce 45 a hole of special contour that is predetermined by the shape of said outer surface of the removable member.

HAROLD H. BAUER.
